UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK, A CORPORATION OF NEW YORK.

TYPEWRITING MACHINE.

Application filed June 7, 1919, Serial No. 302,518. Renewed June 27, 1922. Serial No. 571,282.

To all whom it may concern:

Be it known that I, FRANK H. ARMSTRONG, a citizen of the United States, and a resident of Auburn, county of Cayuga, and 5 State of New York, have invented certain new and useful Improvements in Typewriting Machines, of which the following is a specification.

This invention relates to improvements 10 in typewriting machines, and more particularly to line-spacing mechanism therefor of the type in which the platen may be rotated relatively to the ratchet wheel for irregular line spacing.

15 The invention has for one of its objects the provision of simple and compact mechanism for connecting and disconnecting the platen roll and line space ratchet wheel which may be mounted between one end of 20 the roll and the usual finger wheel without necessitating a material increase in the length of the platen shaft.

Another object of the invention is to provide an irregular line-spacing mechanism 25 having a minimum number of parts and so constructed that the several parts thereof may be readily and inexpensively made from sheet metal, thus reducing the cost of manufacture and also reducing the weight 30 of the machine.

Further objects of the invention are to provide a simple, light, compact and durable friction clutch mechanism for connecting and disconnecting a platen and ratchet 35 wheel which will securely hold the platen and ratchet wheel against relative rotation when in locking position and which may be easily and quickly operated to lock and release the ratchet wheel.

40 In the drawings, Fig. 1 is a front elevation showing the improved line-spacing mechanism, the parts being shown in position for releasing the ratchet wheel;

Fig. 2 a transverse section on the line 45 II—II of Fig. 1;

Fig. 3 a longitudinal sectional view showing the parts in position for locking the platen and ratchet wheel to rotate in unison;

50 Fig. 4 a transverse section on the line IV—IV of Fig. 3;

Fig. 5 a perspective view of the gripping member;

Fig. 6 a transverse section on the line 55 VI—VI of Fig. 3;

Fig. 7 a transverse section on the line 60 VII—VII of Fig. 3; and

Fig. 8 a fragmentary end elevation showing the inner side of the rotatable operating device or finger wheel.

Referring to the drawing by numerals, 1 designates the platen roll which is rigidly held to the platen shaft 2 by suitable set screws 3 tapped through sleeves 4 held to each end of the platen roll. The platen shaft 2 is journaled in the usual end brackets 5 formed at the opposite ends of the base plate 6 of a suitable platen carriage. The platen carriage may be of any suitable construction, such as that shown in my co-pending application Serial No. 196,867, filed October 16, 1917.

At the left-hand end of the platen roll the shaft 2 extends loosely through a sleeve 7 which extends through an aperture in the 75 adjacent end bracket 5. The ratchet or feed wheel 8, preferably stamped from sheet metal, is rigidly secured in any suitable manner to a hub 9 held to sleeve 7 to rotate therewith by means of a suitable set screw 10. The ratchet wheel 8 is normally held against rotation by a detent roller 11 journaled in the free end of a resilient arm or curved spring 12, one end of which is secured to the base plate 6 of the carriage 85 by a screw 13. Any suitable means may be employed for rotating the ratchet wheel for regular line spacing, such for example as either of the line-spacing mechanisms shown in my co-pending applications Serial 90 No. 256,684 and Serial No. 256,685, filed Oct. 3, 1918. The inner end of sleeve 7 preferably abuts against the outer end of sleeve 4 and the outer end of the hub 9 of the ratchet wheel preferably abuts against the 95 inner face of the adjacent end bracket 5. The sleeve 7 is also preferably formed with an annular flange or collar adjacent the outer face of the end bracket. The sleeve 7 and the ratchet wheel are thus held against lateral movement.

A friction disk or drum 14 is rigidly held to the outer end of sleeve 7 exteriorly of the end bracket 5, said disk or drum being preferably stamped from sheet metal. A finger 105 wheel 15, for rotating the platen independ-

ently of the line-spacing lever, is fixed to the left-hand end of the platen shaft 2, and a similar finger wheel is also preferably fixed to the oposite end of the shaft. The 5 finger wheel 15 is preferably fixed to a sleeve 16 held to shaft 2 by a set screw 17. An auxiliary finger wheel or cupped gripper actuating disk or drum 18 is loosely mounted on the platen shaft 2 intermediate the sleeves 10 7 and 16, to rotate in either direction relatively to the shaft a limited distance. The wheel 18 is preferably formed of sheet metal.

A gripping device or ratchet wheel locking member 19, of general disk form, is 15 mounted between the adjacent faces of the actuating drum 18 and disk 14, said member being formed with a central circular aperture 20 through which the platen shaft 2 extends. The aperture 20 is larger in 20 diameter than the platen shaft to permit movement of the gripping member transversely of the platen shaft at any angle to the plane of the base plate 6 of the carriage. The gripping member is stamped from sheet 25 metal and formed with a pair of oppositely disposed, curved, resilient arms 21 offset at the inner face of said member. The curved arms 21 extend in opposite directions concentrically with the edge of the disk-like 30 gripper member, the free ends thereof being spaced apart and bent inwardly beyond the periphery of the gripper member to form a pair of spaced gripping jaws 22 adapted to engage the periphery of the disk 14 at 35 spaced points. The jaws 22 are preferably bent tangentially to the periphery of disk 14, as shown, so that one edge of the end of each jaw will grip the disk 14, and the gripping jaws are preferably treated to 40 harden the metal.

Intermediate the jaws 22 the gripper member 19 is formed with a laterally bent lug 23 which extends through a cam slot 24 formed in the auxiliary finger wheel or 45 gripper actuating drum 18. The lug 23 also extends through a slot 25 formed in a guiding and driving member or plate 26 rigidly held to the inner end of sleeve 16 and housed within the cupped drum 18. The slot 25 extends at a right angle to the 50 axis of the platen shaft and guides the gripping member during its locking and releasing movements, and the plate 26 and lug 23 form a driving connection between the 55 platen shaft 2 and the gripping member 19 and its actuating wheel or drum 18, so that the gripping member and its actuating drum will rotate with the platen roll. The cam slot 24 permits a limited relative movement 60 between the actuating drum 18 and the platen shaft 2 in either direction for shifting the gripping member 19 transversely of the platen shaft. When the auxiliary finger wheel or drum 18 is rotated to the position 65 shown in Figs. 1 and 2 and lug 23 rides

into the high part of cam slot 24, the aperture 20 in the gripping member 19 is concentric with the platen shaft and the jaws 22 merely touch the periphery of friction disk 14, and the platen roll may be rotated in either direction through the medium of the finger wheel 15 while the ratchet wheel 8 is held stationary by detent roll 11. By rotating the drum 18 in the opposite direction lug 23 will be forced into the low part of cam slot 24 and the resilient arms 21 carrying jaws 22 will be placed under tension and said jaws will thus be forced into tight frictional engagement with the periphery of disk 14. The ratchet wheel will thus be locked to rotate with the platen so that the platen may be rotated for regular line spacing by a suitable line spacing lever and pawl.

It will be obvious that the cam slot 24 may be so formed that the gripping jaws 22 will be shifted entirely out of contact with the disk 14 when the lug 23 is in the high part of the slot, if desired. It will also be obvious that the form of the gripping member may be varied, and that the means for shifting said member may be also varied without departing from the spirit of the invention. By employing rotatable means for actuating the ratchet locking and releasing means I avoid the inconvenient and awkward operation of shifting an operating handle for controlling the ratchet release means longitudinally of the platen. By providing a transversely shiftable gripping member having spaced resiliently supported jaws it will be seen that the gripping jaws will adjust themselves to compensate for any slight inequalities in the parts.

What I claim is:

1. In a typewriting machine, the combination of a platen, a line-spacing feed wheel, and means adapted to connect the platen and feed wheel to rotate in unison or to disconnect the same to permit rotation of the platen relatively to the feed wheel, said means comprising a clutch member rotatable with the feed wheel and a member rotatable with the platen and manually shiftable bodily transversely of the platen having a pair of integral resilient arms the free ends of which are formed with jaws adapted to grip said clutch member.

2. In a typewriting machine, the combination of a platen, a line-spacing feed wheel, and means adapted to connect the platen and feed wheel to rotate in unison or to disconnect the same to permit rotation of the platen relatively to the feed wheel, said means comprising a clutch member having a friction surface concentric with the axis of the platen rotatable with the feed wheel and a sheet metal gripping member rotatable with the platen and shiftable transversely of the platen and having a pair of integral resilient arms the free ends of which are

bent laterally toward said friction surface to form gripping jaws.

3. In a typewriting machine, the combination of a rotatable platen, a line spacing feed wheel, and clutching means for connecting and disconnecting the platen and feed wheel comprising a rotatable clutch member having a friction surface concentric with the axis of the platen, a rotatable and bodily 10 shiftable clutch member, a pair of resiliently supported gripping jaws carried by said shiftable member, and means for shifting said member bodily transversely of the platen to cause said jaws to grip the friction surface of the other member under 15 spring tension.

4. In a typewriting machine, the combination with a rotatable platen and a line-spacing feed wheel therefor, of a pair of 20 clutch members rotatable with said platen and wheel respectively, one of said clutch members having a friction surface, a pair of resiliently supported gripping jaws carried by the other clutch member, and a finger 25 wheel normally rotatable in unison with the jaw-carrying clutch member and manually rotatable in opposite directions relatively to said member for shifting the member to cause the jaws carried thereby to grip and 30 release the friction surface of the other clutch member.

5. In a typewriting machine, the combination with a platen and a line spacing feed wheel, of a clutch member rotatable with 35 the feed wheel having a friction surface extending in a circle around the axis of the platen, a second clutch member rotatable with the platen, a pair of resiliently supported jaws carried by the second clutch 40 member, a hand-operated device normally rotatable with the second clutch member, and a connection between said device and the second clutch member for shifting said member transversely of its axis of rotation to 45 cause the jaws to grip and release the friction surface of the first clutch member, said hand-operated device being manually rotatable in opposite directions relatively to the second clutch member for shifting said 50 member.

6. In a typewriting machine, the combination of a platen shaft, a platen roll held to the shaft to rotate therewith, a finger wheel mounted on one end of the shaft to rotate therewith, a line space feed wheel loosely mounted on the shaft between the finger wheel and the adjacent end of the roll, means forming a circular friction surface rotatable with the line space wheel between 55 said wheel and the finger wheel, a clutch 60 member rotatable with the platen roll located between the finger wheel and line space wheel and provided with resiliently supported jaws spaced apart around said 65 friction surface, and hand-operable means

located between the finger wheel and line space wheel and shiftable relatively to said member for bodily moving the member to cause said jaws to grip and release the friction surface.

7. In a typewriting machine, the combination of a platen shaft, a platen roll held to the shaft to rotate therewith, a finger wheel mounted on one end of the shaft to rotate therewith, a line space feed wheel 70 loosely mounted on the shaft between the finger wheel and the adjacent end of the roll, a clutch member having a circular friction surface rotatable with the line space wheel between said wheel and the finger 80 wheel, a plate-like member between the finger wheel and line space wheel rotatable with the platen roll and shiftable edgewise transversely of the roll, jaws resiliently held to said plate-like member and spaced apart circumferentially of the gripping surface of the clutch member, and a disk-like element between the finger wheel and line space wheel rotatable in opposite directions about the axis of the platen roll relatively to said 85 plate-like member and operatively connected to shift the member edgewise when rotated relatively thereto.

8. In a typewriting machine, the combination of a platen shaft, a platen roll held 90 to the shaft to rotate therewith, a finger wheel fixed to one end of the platen shaft, a line spacing wheel loosely mounted on the shaft between the finger wheel and the adjacent end of the platen roll, and means 100 located entirely exteriorly of the platen roll for connecting the line spacing wheel and platen roll to rotate in unison, said means comprising a disk rotatable with the ratchet wheel and a manually shiftable sheet metal 105 gripping member rotatable with the platen roll and movable transversely of the axis of rotation thereof and formed with a pair of integral resilient arms bent at their free ends to provide oppositely inclined jaws adapted 110 to grip the periphery of said disk at circumferentially spaced points.

9. In a typewriting machine, the combination of a platen shaft, a platen roll held to the shaft to rotate therewith, a line space 115 wheel loosely mounted on the shaft, a disk rotatable with said line space wheel, a locking member adapted to grip the periphery of said disk rotatable with the platen roll and shiftable bodily radially of said roll 120 to and from locking position, and hand-operated means mounted on the platen shaft and rotatable in opposite directions relatively thereto for actuating said locking member.

10. In a typewriting machine, the combination of a platen shaft, a platen roll held to the shaft to rotate therewith, a line space wheel loosely mounted on the shaft, a disk 130 having a smooth outer edge rotatable with

4

said line space wheel, a locking member adapted to frictionally engage the outer edge of the disk rotatable with the platen roll and shiftable bodily transversely of the axis of said roll to and from locking position, hand-operated means mounted on the platen shaft and rotatable in opposite directions relatively thereto for actuating said locking member, a finger wheel fixed to one end of the platen shaft, and a detent yieldably engaging the line space wheel.

11. In a typewriting machine, the combination of a platen roll, a line space ratchet wheel, a clutch member having a circular friction surface rotatable with the ratchet wheel, a second clutch member provided with a pair of oppositely inclined jaws tangential to said friction surface, means connecting said second clutch member to rotate with the platen roll and move bodily transversely of the roll, and hand operable means for shifting said second clutch member transversely of the roll to cause the jaws thereon to grip and release the friction surface.

12. In a typewriting machine, the combination of a platen shaft, a platen roll held to the shaft to rotate therewith, a line space wheel loosely mounted on the platen shaft, a friction disk rotatable with said line space wheel, a locking member adapted to grip the outer edge of said disk rotatable with the platen roll and shiftable bodily transversely of the axis of said roll to and from locking position, a finger wheel fixed to one end of the platen shaft, a detent yieldably engaging the line space wheel, an auxiliary finger wheel held against endwise movement on the platen shaft and rotatable in opposite directions relatively thereto, and a cam connection between said auxiliary finger wheel and the locking member for moving said member transversely of the axis of the platen roll.

13. In a typewriting machine, the combination of a platen shaft, a platen roll held to the shaft to rotate therewith, a line space wheel loosely mounted on the platen shaft, a clutch member having a circular friction surface rotatable with said line space wheel, a member provided with jaws adapted to grip said friction surface at circumferentially spaced points rotatable with the platen roll and shiftable bodily transversely of the axis of said roll to and from locking position, and hand operated rotary cam means mounted on the platen shaft for shifting the locking member to and from locking position.

14. In a typewriting machine, the combination of a platen shaft, a platen roll fixed on the shaft, a line space ratchet wheel loose on the shaft, a clutch member having a circular friction surface rotatable with the

wheel, a second clutch member rotatable with the roll, resilient gripping elements supported on said second clutch member for gripping said surface under tension, and hand operated rotary cam means rotatable in opposite directions about the platen shaft for shifting said second clutch member bodily in a path intersecting the plane of said friction surface.

15. In a typewriting machine, the combination of a platen shaft, a platen roll fixed on the shaft, a line space wheel loose on the shaft, a sheet metal disk rotatable with the wheel, a sheet metal member adjacent said disk rotatable with the roll and shiftable in a path at an angle to the axis of the roll, means resiliently held to said member for gripping the periphery of said disk under tension, a narrow auxiliary finger wheel mounted on the shaft and rotatable in opposite directions relatively thereto, means forming a pin-and-slot cam connection between said auxiliary finger wheel and member for shifting the member relatively to the disk, and a main finger wheel fixed on the end of the platen shaft adjacent said auxiliary finger wheel.

16. In a typewriting machine, the combination of a platen shaft, a platen roll fixed thereon, a line space wheel loosely mounted on the shaft, a disk held to rotate with said wheel, a shiftable member, a pair of resilient arms held to said member at one end and provided at their opposite ends with jaws adapted to grip the periphery of said disk, means for supporting said member to rotate with the platen shaft and to permit movement thereof transversely of said shaft, and hand-operated rotary cam means mounted on the platen shaft and operatively connected to shift said member transversely of the shaft to cause said jaws to grip the disk under tension.

17. In a typewriting machine, the combination of a platen shaft, a platen roll fixed thereon, a line space wheel loosely mounted on the shaft, a disk held to rotate with said wheel, a shiftable member, a pair of resilient arms held to said member at one end and provided at their opposite ends with jaws adapted to grip the periphery of said disk, means for supporting said member to rotate with the platen shaft and to permit movement thereof transversely of said shaft, and a finger wheel mounted on the platen shaft to rotate relatively thereto and having a cam slot, said shiftable member having a lateral projection engaging in said cam slot.

18. In a typewriting machine, the combination of a platen shaft, a platen roll fixed thereon, a line space wheel loosely mounted on the shaft, a disk held to rotate with said wheel, a guiding and driving plate having a slot extending transversely of the

axis of the platen shaft, a finger wheel loosely mounted on the shaft adjacent said plate and provided with a cam slot, a member movable transversely of the axis of the 5 platen shaft, a laterally extending arm on said member extending through the cam slot in said finger wheel and the slot in said plate, and a pair of gripping jaws held to said member adapted to grip the periphery 10 of said disk.

19. In a typewriting machine, the combination of a platen shaft, a platen roll fixed thereon, a line space wheel loosely mounted on the shaft, a disk held to rotate with said wheel, a guiding and driving plate having a slot extending transversely of the axis of the platen shaft, a finger wheel loosely mounted on the shaft adjacent said plate and provided with a 15 cam slot, a member movable transversely of the axis of the platen shaft, a laterally extending arm on said member extending through the cam slot in said finger wheel and the slot in said plate, and a pair of 20 resilient arms held to said member at one end having their free ends bent toward the periphery of said disk to form jaws for gripping the periphery of the disk.

20. In a typewriting machine, the combination of a platen shaft, a platen roll fixed on the shaft, a sheet metal line space wheel loosely mounted on the shaft, a sheet metal disk held to rotate with the line space wheel, a finger wheel fixed to the end of the 30 shaft adjacent the line space wheel, a sheet metal auxiliary finger wheel loosely mounted on the platen shaft between said fixed finger wheel and said disk and provided with a cam slot, a sheet metal plate held to rotate with the platen shaft and formed with a slot extending radially of the axis of the shaft, and a sheet metal gripper member having an enlarged opening through which the shaft extends and also formed with a 35 laterally bent lug extending through the slots in said plate and auxiliary finger wheel, said gripper member being formed with a pair of integral arms the free ends of which extend toward said lug and are 40 bent to form jaws adapted to grip the periphery of said disk.

21. In a typewriting machine, the combination of a platen, a line space wheel, a sheet metal non-shiftable clutch member rotatable with the line space wheel and having a friction surface surrounding the axis of the platen, a sheet metal shiftable clutch member, a sheet metal driver connecting the shiftable clutch member to rotate with the 50 platen, a sheet metal disk rotatable about the axis of the platen relatively to the shiftable clutch member and formed with a peripheral annular finger-grip flange, and means forming a direct cam connection between said disk and the shiftable clutch 60

member for shifting said member into and out of driving relation with the non-shiftable member.

22. In a typewriting machine, the combination of a platen, a line space wheel, 70 cooperating clutch members one of which is rotatable with the platen and the other with the line space wheel, and a finger wheel rotatable relatively to one of said members and provided with cam means co-acting with said member to shift the same transversely of the axis of rotation thereof in a plane parallel with the planes of the finger wheel and the other clutch member into and out of driving relation with the other 80 member and lock the shiftable member in either of its shifted positions.

23. In a typewriting machine, the combination of a platen, a line space wheel, a disk rotatable with the line space wheel, a 85 plate-like driver rotatable with the platen, a plate-like metallic member shiftable edgewise transversely of the platen and provided with laterally offset jaws adapted to grip the periphery of said disk, means forming a pin-and-slot driving connection between the driver and said member, a finger disk adjacent said member and driver rotatable in opposite directions about the axis of the platen relatively to the member and 90 driver, and a direct cam connection between said disk and member for shifting the member edgewise when the disk is rotated and locking the member in its shifted position.

24. In a typewriting machine, the combination of a platen, a line space wheel, a clutch member having a friction surface rotatable with the line space wheel, a plate-like device rotatable with the platen and carrying jaws adapted to grip said friction 105 surface at circumferentially spaced points, an actuating disk rotatable relatively to the platen, and a direct cam connection between said actuating disk and the gripping device for shifting the device transversely of the 110 axis of the platen to and from gripping position.

25. In a typewriting machine, the combination of a platen, a line space wheel, a disk rotatable with the line space wheel, a 115 member rotatable with the platen having resilient arms supporting jaws adapted to grip the periphery of said disk at circumferentially spaced points, and means rotatable relatively to the platen in opposite directions about the axis of the platen for shifting the member transversely of the axis of the platen to and from gripping position.

26. In a typewriting machine, the combination of a platen, a line space wheel, a clutch element having a gripping surface concentric with the axis of the platen rotatable with said wheel, a member rotatable with the platen, a resiliently supported 125 130

- jaw carried by said member, and means for shifting said member bodily at an angle to the axis of the platen to force said jaw into engagement with said surface under tension.
- 5 27. In a typewriting machine, the combination of a platen, a line space wheel, a disk rotatable with said wheel, a gripper member rotatable with the platen, a resiliently supported jaw carried by said member, and means for moving said member transversely of the axis of rotation of the platen to force said jaw into engagement with the periphery of said disk under tension.
- 10 28. In a typewriting machine, the combination of a platen, a line space wheel, a disk rotatable with said wheel, a gripper member rotatable with the platen having a pair of integral resilient arms the adjacent free ends of which are bent to form jaws adapted to grip the periphery of said disk, and means for moving said member relatively to the platen and disk to force said jaws into engagement with the periphery of the disk under tension.

This specification signed this 16, day of May.

FRANK H. ARMSTRONG.
